Primary Examiner — Eric Goodman*Assistant Examiner* — Christian P McLean*(74) Attorney, Agent, or Firm* — Workman Nydegger(57) **CLAIM**

The ornamental design for a display screen with icon, as shown and described.

DESCRIPTION

The sole FIGURE is a front view of a display screen with icon showing our new design.

The broken line showings of the display screen, electronic device, and portions of the interface form no part of the claimed design. The broken lines are for environmental purposes only and form no part of the claimed design.

1 Claim, 1 Drawing Sheet(56)
